UNITED STATES PATENT OFFICE.

ANDERS GUSTAF THEODOR ÖFVERSTROM, OF SUNDSVALL, SWEDEN.

HANDLE-BAR FOR VELOCIPEDES.

SPECIFICATION forming part of Letters Patent No. 642,357, dated January 30, 1900.

Application filed July 20, 1899. Serial No. 724,485. (No model.)

To all whom it may concern:

Be it known that I, ANDERS GUSTAF THEODOR ÖFVERSTRÖM, merchant, a subject of the King of Sweden and Norway, and a resident 5 of Sundsvall, Sweden, have invented certain new and useful Improvements in Steering-Bars for Velocipedes and the Like, (for which I filed application in Sweden the 1st day of May, 1899, under No. 765,) of which the following is a specification, reference being had 10 therein to the accompanying drawings.

This invention relates to steering-bars for velocipedes and the like, which bars generally consist of two separate parts which are 15 movably connected to the stem of the steering-fork (fore-wheel fork) and which can be adjusted into different positions by being turned on their axes.

My invention aims to provide adjustable 20 and removable steering-arms which are especially adapted to be used in velocipedes. The steering-bar arms hitherto commonly used in velocipedes are integral with one another and are inserted in a cross-sleeve, forming 25 one piece with the stem of the steering-fork or firmly connected to the same. According to this invention the arms of the bar, which are inserted in a cross-sleeve in the same manner as the arms of previous constructions, can be telescoped and are provided 30 in their walls with one or more holes or perforations which correspond to one another when the arms are telescoped. In said holes enters a bolt or bolts actuated by a spring or 35 springs and located in the stem of the steering-fork, said bolt or bolts serving to lock the arms in their adjusted position. By turning the steering-bar arms so as to cause the bolt or bolts to enter into holes having one position or another the arms can thus be locked 40 in their different positions.

The invention is illustrated in the accompanying drawings.

Figure 1 shows in elevation a part of a 45 steering device arranged according to this invention. Fig. 2 shows a section along the line 11 in Fig. 1. Fig. 3 shows a detail.

A and B designate the inner ends of the two arms of the steering-bar.

50 C is the tubular stem of the steering-fork,

and with the upper end of said stem is a cross-sleeve D, united by soldering. Near the sleeve D is a piece E, fixed in the tubular stem C. A hole F is made through said piece and through the sleeve D. Below the piece E 55 there is an annular piece G, fixed in the tube or stem C. A bolt or bar I, surrounded by a spiral spring H, is located in the tube or stem C and passes through the annular piece G, the reduced upper end J of said bolt or bar 60 passing through the hole F in the piece E. A screw K enters into the tube C through a slot L in the wall of the tube and is screwed into the thick part of the bolt I near the reduced end or pin J. The one end of the 65 spiral spring H rests against the screw K, while the other end of the same is supported by the annular piece G. By depressing the screw K the bolt I is moved downward in the tube C, and when the screw is released the 70 bolt returns to its original position, acted upon by the spring.

Near its one end the arm A is provided with three holes, the centers of which are located on the bow of a circle, and on a greater distance from said end there is a conical ring M, which tapers in the direction of the end in question. The other arm B has a corresponding ring M'. In the inner end of the arm B is fixed a tube N, having a less diameter than 75 the arms A and B and provided with holes L', corresponding to the holes L.

When putting the parts together, the ends of the arms A and B are introduced into the sleeve D from opposite sides, whereby the 85 tube N is passed into the arm A, the screw K being depressed during this operation. This being made, the arms A and B are so adjusted that when releasing the screw K the pin J enters into a pair of the holes L and L', thereby locking the arms A and B in position. By depressing the screw K and by turning the arms A and B the pin J can be caused to enter into another pair of holes, so that the arm of the steering-bar can be kept in different 90 positions.

Having now described my invention, what I claim as new, and desire to secure by Letters Patent, is—

The combination with a stem C, of a perfo- 100

rated piece E and an annulus G fixed therein, a cross-sleeve D secured thereto, a handle-bar A having a conical ring M, and a series of holes, an arm B having a conical ring M' and a tube N provided with holes, a bolt I in the stem, and a spring H engaging the said bolt.

In witness whereof I have hereunto signed my name in the presence of two subscribing witnesses.

ANDERS GUSTAF THEODOR ÖFVERSTRÖM.
